UNITED STATES PATENT OFFICE.

ALFRED E. GOODWYN, OF BLUEFIELD, WEST VIRGINIA.

FAUCET.

1,019,317.

Specification of Letters Patent. Patented Mar. 5, 1912.

Application filed March 16, 1911. Serial No. 614,886.

To all whom it may concern:

Be it known that I, ALFRED E. GOODWYN, a citizen of the United States, residing at Bluefield, in the county of Mercer, State of West Virginia, have invented certain new and useful Improvements in Faucets; and I do hereby declare the following to be a full, clear, and exact description of the invention, such as will enable others skilled in the art to which it appertains to make and use the same.

This invention relates to an improvement in faucets of that type adapted to be operated by contact with a glass or the like.

15 This invention is particularly adapted for use in connection with soda-water fountains and other places which necessitate a quick acting faucet.

The principal object of this invention is 20 to provide a novel construction of faucet wherein the liquid is discharged centrally into the glass or other receptacle.

Another object of the invention is to provide a faucet of the character described, 25 which is provided with a novel construction of valves.

A further object of the invention is to provide a faucet for the purpose described which is provided with a novel form of locking means whereby the said valve may be 30 locked against its seat.

A still further object of the invention is to provide a device of this character which is composed of a minimum number of parts, 35 is therefore simple in construction, and is cheap to manufacture.

With these and other objects in view, the invention consists in the construction and 40 novel combination of parts hereinafter fully described, illustrated in the accompanying drawings, and pointed out in the claims hereto appended; it being understood that various changes in the form, proportion, size and minor details of construction, with- 45 in the scope of the claims, may be resorted to without departing from the spirit or sacrificing any of the advantages of the invention.

In the drawings: Figure 1 is a perspective 50 view of the faucet, Fig. 2 is a vertical sectional view through the same showing the valve locked, Fig. 3 is a similar view but showing the valve unlocked and in its raised position, Fig. 4 is a horizontal sectional view 55 taken on the line 4-4 of Fig. 2, Fig. 5 is a

detail perspective view of the outlet tube and the valve, Fig. 6 is an enlarged perspective view of the key, and Fig. 7 is an enlarged perspective view of the locking bolt.

60

Like reference numerals designate corresponding parts in all the figures of the drawing.

Referring to the drawing, the invention comprises a hollow head 5 which includes 65 a top 6 and a side wall 7. Extending radially from the wall 7 and communicating with the interior of the head, is a barrel 8 having its outer end 9 exteriorly threaded for engagement with any suitable liquid 70 containing tank. Integral with the wall 7 and depending therefrom is a tapering tubular extension 10 constituting a valve-seat and having an open lower end 11.

The invention further comprises a tubular shell 12 having an open lower end 13 and having its upper end 14 connected integrally with the extension 10 at a point intermediate the ends of said extension. By this construction it will be observed that the 75 lower end portion of the extension 10 constitutes a flange 15, which is disposed within said tubular shell 12 to form a consequent annular recess 16.

Seated within the extension 10 is a valve 80 85 17, and disposed between the valve and the top 6 of the head is a coil spring 18, which normally tends to keep said valve seated against the extension 10. The lower face 19 of the valve 17 is formed with an inwardly extending annular recess 20 having 90 threads formed on its outer wall.

The invention further comprises an outlet tube 21 having its upper end exteriorly threaded and engaged within the threaded 95 recess 20 of the valve. The lower end of said tube projects below the lower end 13 of the tubular shell 12, and secured thereto are radially extending and upwardly bowed arms 23-23 adapted to be engaged by a 100 glass, or other suitable receptacle. A funnel 24 is disposed around the outlet tube 21, and has its smaller end 25 connected to said tube. The outer end 26 of the funnel has an outer circumference slightly less than the 105 interior circumference of the tubular shell 12. Thus it will be observed that when the outlet tube 21 is elevated, the upper end 26 of the funnel is disposed behind the flange 15 and within the recess 16. Formed in the 110

outlet tube 21 adjacent the lower end 25 of said funnel, is a plurality of outlet openings 27.

The extension 10 is provided with an exterior enlargement 28, which is disposed in the plane of the top of the valve 17 when said valve is seated. Formed in the outer face of said enlargement 28 is a seat 29, and communicating with said seat and with the interior of the extension 10 is a threaded opening 30. Seated within the opening 30 is the shank 31 of a bolt, said bolt being provided with a head 32 which is normally disposed within the seat 29. This head is provided on its outer face with a plurality of recesses 33 arranged in any suitable manner. The shank 31 normally projects above and engages the valve 17 to retain the latter in its closed position. An operating key 34 is provided with a head 35, and projecting from said head is a plurality of fingers 36 adapted for engagement with the recesses 33 of the screw. By means of this tool it will be obvious that the set screw may be easily rotated and withdrawn from the path of movement of said valve 17.

Disposed around the outlet tube 21 is a plurality of tubular guides 37, and these guides are each retained in place by means of radially extending arms 38, the outer ends thereof being suitably connected to the tubular shell 12.

From the foregoing, it will be observed that when a glass or other receptacle is pushed upwardly against the arms 23 of the outlet tube 21, the valve 17 will be unseated and the funnel 24 will be disposed in rear of the flange 15 as before described. As a result, liquid will flow through the barrel 8 into the head 5, through the extension 10 and into the funnel 24, through the openings 27 and out through the lower end 22 of the tube 21, and into the glass. As soon as the upward pressure upon the arms 23 has been relieved, the spring 18 will cause the valve 17 to quickly seat itself.

Depending from the lower end of the outlet tube 21 and below the arms 23 is a nozzle 39 which is adapted to be positioned within the mouth of a bottle. This nozzle is formed integral with the outlet tube and constitutes a means for directing the passage of liquid into the bottle, thereby avoiding any danger of the liquid being scattered. Secured to the inner end 9 of the barrel 8 is a screen 40 of any suitable construction, which will prevent any foreign matter from passing through the spigot.

What is claimed is:

1. A faucet comprising in combination, a head, a valve seat connected to the head, a valve, a tubular shell extending from the valve seat, an outlet tube disposed within the shell and connected to the valve and provided with an opening near its inner end, a

funnel extending from the tube below said opening, said funnel coöperating with the shell to guide the liquid into the opening of the tube when the valve is open, and a spring disposed between the valve and the head for normally holding the valve closed. 70

2. A faucet comprising in combination, a head, a valve seat connected to the head, a valve, a tubular shell extending from the valve seat, an outlet tube disposed within the shell and connected to the valve and provided with an opening near its inner end, arms extending radially from the projecting end of the outlet tube and coöperating with the end of the shell to limit the movement of said tube, a funnel extending from the tube below said opening, said funnel coöperating with the shell to guide the liquid into the opening of the tube when the valve is open, and a spring disposed between the valve and the head for normally holding the valve closed. 80

3. A faucet comprising in combination, a head, a tapering tubular extension constituting a valve seat integral with said head, a valve, a tubular shell having its upper end connected with the extension at a point intermediate the ends thereof, an outlet tube disposed within the shell and connected to the valve and provided with an opening near its inner end, a funnel extending from the tube below said opening, said funnel coöperating with the shell to guide the liquid into the opening of the tube when the valve is open, the outer end of the funnel being adapted in one position to engage behind the lower end of the valve seat, and a spring disposed between the valve and the head for normally holding the valve closed. 90

4. A faucet comprising in combination, a hollow head including a top and a side wall, a tapering tubular extension constituting a valve seat integral with the side wall and provided with an open end, a valve, a tubular shell having its upper end connected integrally with the extension at a point intermediate the ends thereof, an outlet tube disposed within the shell and having its upper end connected to the valve and its lower end projecting below the lower end of the shell, 110 said tube having its wall provided with an opening disposed below the valve seat, a funnel disposed around the outlet tube and having its smaller end connected thereto below the opening, the outer end of the funnel projecting upwardly and adapted in one position to be disposed in rear of and in contact with the lower end of the valve seat, said funnel coöperating with the shell to guide the liquid into the opening of the tube 120 when the valve is open, radially projecting arms secured to the lower end of the tube, and a spring interposed between the head and the valve for normally holding the valve closed. 125

5. A faucet comprising in combination, a hollow head including a top and a side wall, a tapering tubular extension constituting a valve seat integral with the side wall and 5 provided with an open end, a valve, a tubular shell having its upper end connected integrally with the extension at a point intermediate the ends thereof, an outlet tube disposed within the shell and having its upper 10 end connected to the valve and its lower end projecting below the lower end of the shell, said tube having its wall provided with an opening disposed below the valve seat, a funnel disposed around the outlet tube and 15 having its smaller end connected thereto below the opening, the outer end of the funnel projecting upwardly and adapted in

one position to be disposed in rear of and in contact with the lower end of the valve seat, said funnel coöperating with the shell to 20 guide the liquid into the opening of the tube when the valve is open, radially projecting arms secured to the lower end of tube, a spring interposed between the head and the valve for normally holding the valve closed, 25 and means carried by the head for locking the valve against movement.

In testimony whereof, I affix my signature, in presence of two witnesses.

ALFRED E. GOODWYN.
